UNITED STATES PATENT OFFICE.

THEODORE LUCE, OF DETROIT, MICHIGAN.

RAILWAY-CAR.

SPECIFICATION forming part of Letters Patent No. 247,260, dated September 20, 1881.

Application filed March 8, 1881. (No model.)

To all whom it may concern:

Be it known that I, THEODORE LUCE, of Detroit, in the county of Wayne and State of Michigan, have invented an Improvement in 5 Railway-Cars, of which the following is a specification.

The nature of this invention relates to certain new and useful improvements in railway-cars, by means of which they may be run, with 10 comparative safety, at a very high rate of speed, and the position of the draw-bar will always regulate the position of the wheels with relation to the rails of a railway-track, so that the liability of the car to leave the track or to 15 run off the same at curves is almost if not entirely obviated.

The invention consists in the peculiar construction of the truck and axle and their combination with each other and a draw-bar pivoted at about midway of its length and adapted to change the position of the wheels with relation to the track, all as more fully herein-after described.

Figure 1 is a bottom plan of a section of a 25 car with my improved truck and draw-bar attached. Fig. 2 is a vertical central cross-section through the center of the truck. Fig. 3 is a longitudinal vertical central section through the draw-bar and truck. Fig. 4 is a perspective view of the lower half of the centrally-pivoted vibrating-plate, which forms the boxes for the inner ends of the axles, and to which the inner end of the draw-bar is secured.

In the accompanying drawings, which form 35 a part of this specification, A represents a journal-box, one of which is secured at each side of the car, directly opposite each other. Their axle-boxes are provided with vertical trunnions a, which are adapted to partially rotate 40 in the boxes b, by means of which the boxes are secured to the car-body.

B represents the axles, of which there is one for each wheel C, the wheels being secured to the 45 axles in the usual manner. The outer ends of the axles run in the boxes A, while the inner ends of the axles terminate in a ball, c, which, with the sockets d, forms the usual ball-and-socket joint, such sockets being in the plate D, which is divided into two parts—upper and lower— 50 Fig. 4 representing the lower part, while the upper part is its counterpart reversed. This

plate is provided with a central hole, e, by means of which (when the two parts which form the plate are properly bolted together) and the king-bolt E the plate is secured to the frame F, which is secured longitudinally to the bottom of the car body and platform. The plate is also provided with a socket, h, within which the inner end of the draw-bar G is pivotally secured by the bolt k. This draw-bar is also secured between the upper and lower parts of the frame F by means of the stud-bolt i, which forms a fulcrum, by means of which the draw-bar is converted into a lever to compel the wheels always to travel on lines parallel to the position of the draw-bar for the time being, as shown in Fig. 1, which shows the relative position of the draw-bar and wheels when the car is passing around a curve. Arrangements of springs H may be made as shown in Fig. 2, 70 or any other desired and convenient arrangement may be made for the purpose. When the front end of the draw-bar is in line with the longitudinal center of the car and parallel with the rails of a track, the wheels will run in lines 75 parallel to such longitudinal center; but when the front end of the draw-bar diverges from said center line it is converted into a lever with a fulcrum, which partially rotates the center plate, D, and compels the wheels to change 80 their position and run upon lines parallel to such position of the draw-bar, thereby almost entirely obviating the danger of derailing the car.

What I claim as my invention is—

1. A truck for a railway-car wherein the wheels are adapted to run upon changing lines always parallel to each other and upon separate axles, journaled to allow the wheels to change direction, said axles being journaled at their 90 outer ends in pivoted boxes, and at their inner ends in turning boxes in a centrally-pivoted plate, substantially as and for the purposes set forth.

2. A pivoted draw-bar, G, connected directly 95 to a centrally-pivoted plate, D, carrying the inner boxes of the independent axles as a means of changing the position of said axles to conform with the varying positions of the draw-bar, substantially as described.

3. In combination with a draw-bar fulcrumed 100 to a railway-car, a central plate which forms

the boxes for the inner ends of independent axles, as a means of changing the position of such axles to conform to the varying positions of the draw-bar, substantially as described.

5 4. The centrally-pivoted plate D, made in two sections, each section being provided with recesses d for receiving the boxes of car-axles, and with a recess, h, for receiving the inner end of a pivoted draw-bar, substantially as and 10 for the purpose specified.

5. In a railway-truck and in combination with boxes A, axles B, and wheels C, the cen-

tral plate, D, and frame F, the parts being constructed, arranged, and operating substantially as and for the purposes specified.

6. In combination with a centrally-pivoted plate, having spherical recesses d with outward openings, the spherical axle-boxes c for receiving the inner ends of independent axles, substantially as and for the purpose specified.

15 THEO. LUCE.
